UNITED STATES PATENT OFFICE.

FRED H. LYSONS, OF SEATTLE, WASHINGTON.

BABY-HAMMOCK.

1,182,185.

Specification of Letters Patent.

Patented May 9, 1916.

Application filed July 22, 1915. Serial No. 41,242.

To all whom it may concern:

Be it known that I, FRED H. LYSONS, a citizen of the United States of America, and resident of Seattle, in the county of King and State of Washington, have invented certain new and useful Improvements in Baby-Hammocks, of which the following is a specification.

My invention relates to hammock beds or 10 cots intended more particularly for the use of babies, and also particularly intended for use upon automobiles.

The object of my invention is to provide a means whereby a child may be comfortably and safely carried upon an automobile without the necessity of having to hold the child in somebody's arms or on a lap, and a means which will also furnish effective protection against winds and the sun.

20 It is a further object to so construct a device of this character that it may be collapsed or folded into a small space when not in use.

My invention comprises the novel parts 25 and combinations which will be hereinafter described and particularly defined in the claims.

In the drawings I have shown my invention in the form of construction which is 30 now most preferred by me.

Figure 1 is a perspective showing the device in position for use and secured as it would be when used upon an automobile. Fig. 2 is a cross sectional elevation of the 35 device in open position. Fig. 3 is a similar view showing the outer edge reduced so as to narrow the surface upon which the baby is to be placed. Fig. 4 shows the position of the device when folded. Fig. 5 is a detail 40 showing the construction of the hook by which it is suspended upon the robe rail of an automobile. Fig. 6 is a cross sectional detail showing the manner of securing the stiffening bar which is at the back edge of 45 the device, and Fig. 7 is a detail showing the manner of connecting the stiffening bar of the canopy with its supporting bar.

This device employs a bottom or supporting section 1, a back or side wall section 2 50 and a canopy or cover section 3, these being formed as a continuous part of the same sheet of fabric. In addition to this I prefer to use a depending flap 4 which more

or less covers the open front of the device and end sections 5 which connect the bottom 55 and top sections. At the open or front edge of the bed section a stiffening rail 10 is secured. At the opposite or back section a stiffening bar 6 is incorporated in and secured to the fabric at the point of joining 60 of the bottom and back sections 1 and 2.

A stiffening bar 61' is also placed at the point of joining of the back section and the top or canopy section 3. In the preferred form of construction, these latter two stiffening bars are formed of an integral piece of heavy wire bent into shape, the ends being joined by the vertical sections 60 and the center, or as many intermediate points as may be desired, by transverse portions 62. 70 As herein shown the portion 62 constitutes the ends of the bar, these being twisted at 63 a sufficient amount to insure their being held in proper relation and having their tips bent about the lower bar 6 so as to form 75 eyes 64. The ends may then be extended toward the back and bent into shape to form a hook 65 which is adapted to be placed over the robe-rail 9.

Near each end of the lower bar 6 of this 80 frame the wire is doubled upon itself and bent into shape to form a hook 61 the shape of which is clearly shown in Figs. 3 and 5. At the point where this hook joins the bottom bar 6, the wires are also preferably 85 twisted enough to hold the two parts secured together. These hooks are provided with a curve 67, which embraces the robe-rail 9, when the device is in use. They are also provided near their tips with a curve 90 68 which embraces the robe rail when the device is folded, as has been shown in Fig. 4. The lower bar 6 of the back frame is 95 preferably secured to the fabric sheet by being inserted within sections 12 of fabric 95 which are stitched to the bottom 1. The central hook 65 does not have the extension 68, as it is designed for use in securing the parts in folded position.

The stiffening bar 7, which is placed at 100 the upper and forward edge of the top 3, is preferably a stiff wire, which has an eye 70 formed in its ends, into which is secured an eye 72 of the supporting bar 71. This bar 71 is a piece of similar wire which has 105 its lower end off-set in any suitable manner,

as shown at 73, so as to form a stop. The extension of the bar 71 beyond this stop, is designed to be inserted within an eyelet or hole formed in the end edge of the bottom 1. 5 The stop 73 cannot pass through this hole and the posts 71 are in this way supported to hold the top in raised position. The location of the hole 74 in the bottom piece, should be between the back edge of the bottom 10 and a point immediately under the bar 7.

The end pieces 5 are secured to the bottom 1 from the rear of the latter to a point 51, which is somewhat back from the forward edge of the bottom. The outer lower corner of the flap 5 is provided, at 52, with one part of a securing means as, for instance, spring buttons or fasteners, the other part of which is secured to the bottom 1, 20 so that it may be secured at this point, or left free, as is shown at the left hand end of Fig. 1. Additional securing means may be provided if desired, as has been shown in the loose flap of Fig. 1.

25 The depending curtain 4 is not fixedly secured to the end sections 5, but is provided with securing members 40 of any suitable character analogous to those described at 52, whereby its lower corners may be secured to the end sections 5.

30 The stiffening bar 10, at the forward or outer edge of the bottom, has straps, or other analogous members 8, secured thereto, whereby it may be connected with any 35 convenient and suitable part of the automobile for support. Short straps 11 are also provided, which are secured at one end to the bottom 1, but have a section corresponding with the width from the point 51 to the 40 bar 10, which are not secured to the bottom. The buckle 13 is secured to the bar 10, whereby the width of the bottom may be adjusted by tightening these belts, thus forming the fold 14, as has been shown in Fig. 3.

45 I prefer to provide pockets at the under side of the bottom section 1, the same being formed by stitching the edges of a piece of fabric 16 to the bottom along three sides, this being done in such a way that the pocket 50 will depend somewhat. The ends of the pocket may be secured with hooks and eyes, spring fasteners or any other suitable means. I have herein shown three such pockets, two of which extend, one from each end lengthwise 55 of the device and the other extends from the front or outer edge transverse thereof. The number and position of these pockets may be varied at will.

When not in use, the device may be folded 60 and then placed so that the hooks 68 engage the robe-rail 9, from which it will then depend in the manner shown in Fig. 4. The outer edge of the bottom should preferably be formed with an eyelet, so placed that it

may be hooked over the central hook 65, as 65 has been indicated in Fig. 4.

Having thus described my invention, what I claim as new, and desire to secure by Letters Patent of the United States of America, is:—

70 1. In a device of the character described, a supporting sheet, a stiffening frame secured along one side of the sheet and having means for engagement with a supporting member and also having a canopy supporting member, a canopy, a stiffening bar 75 engaging the outer edge of the canopy, and supporting posts supporting the ends of said bar from the said sheet.

2. A hammock bed comprising a bottom 80 or supporting sheet, a canopy comprising a back wall extending upward from one edge of the supporting sheet, and a top, a frame separating the back edges of the bottom and supporting the back wall and provided 85 with means for engagement with a fixed support, and foldable supporting members for the forward edge of the canopy.

3. A hammock bed comprising a bottom 90 or supporting sheet, provided with means for supporting engagement along opposite side edges, a side wall connected with one side edge and a top extending from the upper edge of said wall, a bar secured along the outer or free edge of the top and supporting posts pivotally connected with the ends of said bar and adapted to be supported 95 by the bottom.

4. A hammock bed comprising a bottom provided with means for supporting engagement along opposite side edges, a wall 100 section secured along one side edge, a supporting frame secured to said wall section, a top secured to the upper edge of said wall section, a bar secured along the outer edge 105 of the top section, supporting bars hingedly connected with the ends of said bar and adapted to engage and be supported from the bottom, and end sections connected with the bottom, back and top sections.

110 5. A hammock bed comprising a bottom provided with means for supporting engagement along opposite side edges, a wall section secured along one side edge, a supporting frame secured to said wall section, 115 a top secured to the upper edge of said wall section, a bar secured along the outer edge of the top section, supporting bars hingedly connected with the ends of said bar and adapted to engage and be supported from the bottom, end sections connected with the bottom, back and top sections, and a flap depending from the outer side edge of the top section.

120 6. A hammock bed comprising bottom, side wall and top sections, a frame secured to the side wall and acting to maintain it extended, said frame having hooks project-

ing therefrom for supporting engagement with a fixed member, and means for supporting the opposite edge of the bottom.

7. A hammock bed comprising bottom, 5 side wall and top sections, a frame secured to the side wall and acting to maintain it extended, said frame having hooks projecting therefrom for supporting engagement

with a fixed member, means for supporting the opposite edge of the bottom, and a collapsible frame supporting the outer edge of 10 the top from the bottom.

Signed at Seattle, Washington, this 14th day of July, 1915.

FRED H. LYSONS.
